SHAPING MACHINE

Ernst Aeberli, Horgen, Switzerland

Application January 26, 1935, Serial No. 3,599
In Germany January 31, 1934

7 Claims. (Cl. 90—9)

My invention relates to a shaping machine and, more particularly, to a machine of this type adapted to cut gears.

It is well known in the art that the cutting tool carried by the reciprocating ram of the shaping machine must be swung out of contact with the blank on the return stroke of the ram. It is customary, for this purpose, to mount the cutter on a holder which is pivotally attached to the ram.

An object of my invention is the provision of a shaping machine adapted to be selectively used for cutting gears of the annular type having interior teeth or gears of the normal type having teeth on their periphery.

It will be readily appreciated that the direction of the pivotal movement of the tool required to avoid contact thereof with the blank during the return stroke of the ram in cutting gears of the annular type is opposite to that required, if gears of the other type are to be cut.

Further objects of my invention are to provide simple means for reversing the direction of such pivotal movement; to provide means insuring the parallel relationship between the tool and the blank during the working stroke of the ram; to provide an oscillatory member adapted to be selectively so connected with the tool holder that the same swings either in a direction towards or in a direction away from the ram upon the return stroke of the latter.

Further objects of my invention will appear from a description of a preferred embodiment following hereinafter and the features of novelty 35 will be pointed out in the claims.

In the drawings,

Fig. 1 shows an elevation of my improved shaping machine, partly in section along line 1—1 of Fig. 3.

Fig. 2 is a sectional elevation of the mechanism for swinging the tool-carrier, the section being taken along line 2—2 of Fig. 3.

Fig. 3 illustrates a section taken along two different planes as indicated by line 3—3 of Fig. 45 2, and

Fig. 4 is a diagram illustrating the function of my invention.

In Fig. 1 I have shown the contouring lines of a shaping machine of a known type similar to that disclosed for instance in the Reissued Patent No. 14,908 to Maag and adapted to produce a gear of the annular type by cutting teeth into the inner surface of an annular blank 30.

The object of my invention is the provision 55 of means which permit the same machine to be

also used for cutting normal gears, for instance a spur-gear indicated in Fig. 1 in dotted lines. The frame 1 of the shaping machine is provided with a vertical guide for a reciprocating ram 2 carrying a bracket 3 which constitutes a journal for a horizontal shaft 4 extending transversely to and in front of the ram 2. The shaft 4 is freely rotatably mounted in two ears of the bracket 3. Intermediate these ears there is pivotally mounted on shaft 4 a tool-carrier 10 in form of a housing which provides a journal for the depending tool-spindle 6. The lower end of the spindle 6 which is journaled in a sleeve formed by the housing 10 projects out of this sleeve and carries the shaping tool 7 in form 15 of a pinion. This pinion serves to cut the interior teeth of the annular blank 30 according to the rolling principle. The required rolling motion which causes the pitch-circle of the gear-shaped tool 7 to roll on the pitch-circle of the 20 interior teeth to be cut is produced in a known manner by an operative connection of the shaft 4 with the rotary work-table 31 having a supporting face for the work or blank 30 extending 25 in angular relation to the movement of the ram. 25 As the means for establishing this operative connection do not form part of my invention, an illustration and description thereof may be dispensed with.

A worm 32 is attached to shaft 4 within the 30 housing 10 and engages a worm-wheel 5 keyed to the upper end of spindle 6. In the operation of the machine, the table 31 is intermittently turned about its vertical axis by the driving motor through a suitable transmission and the 35 spindle 6 is simultaneously rotated at such a speed that the pitch-circle of the cutting pinion 7 rolls along the pitch-circle of the teeth to be cut. While the blank 30 and the spindle 6 pause in their intermittent movement, the ram 2 is 40 moved downward.

During the movement of the ram 2 in the cutting direction, for instance in the downward direction, the tool 7 is brought by a suitable pivotal movement of the housing 10 about the shaft 4 to the operative position shown in Fig. 1 in which the spindle 6 extends in the plane of movement of the ram and in accurate parallel relationship to the axis of the blank. During the return stroke of the ram, however, the tool 45 is swung or moved to position to incline in one direction relative to the plane of movement of the ram and away from the blank 30 in order 50 to prevent injury of the tool by the intermittent rotary movement of the tool and blank. 55

For this purpose, I have devised my novel mechanism illustrated in Figs. 2 and 3 which may be so set at the option of the operator that the direction of the pivotal movement of the tool-carrier may be reversed depending on the particular use to which the machine is to be put, that is to say, whether the teeth of gears of the annular type or gears of the normal type are to be cut. I shall now proceed to describe this mechanism 5 assuming that the working stroke of the tool is the downward stroke and the return-stroke the upward stroke.

A vertical rack 11 is attached to the frame 1 of the machine and meshes with a gear 12 rigidly 15 attached to a shaft 13. The ends of this shaft are journaled within vertical side-walls of the bracket 3 as indicated in Fig. 3, so that the shaft will be alternately turned in opposite directions during the reciprocatory motion of the 20 ram. On the shaft 13, there is mounted a bushing 14 adapted to be frictionally driven by the shaft through a slip-clutch. This is accomplished by having the shaft formed with a shoulder 33, and the bushing 14 frictionally held 25 in contact therewith by a ring 34 which is slidably mounted on the shaft 13, but suitably secured against relative rotation thereto by a key and is acted upon by a helical spring 35 bearing 30 against a nut 36 carried by a threaded portion of shaft 13.

Moreover, the bracket 3 is formed integral with two lugs 37 and 38 (Fig. 3) embracing a projection 39 of the tool-carrier 10. A horizontal shaft 17 is mounted in bores of the lugs 35 37 and 38. As shown in Fig. 3, the bore of lug 37 is of reduced diameter with regard to that of lug 38. That portion of shaft 17 which extends between the lugs 37 and 38 and through the projection 39 forms an eccentric 40. A square block 19 is mounted on the eccentric and is slidably 40 guided between the vertical side-walls 9 of a slot provided in the projection 39 of the tool-holder 10.

The shaft 17 projects beyond the lug 38 to the 45 left with reference to Fig. 3 and its free end carries a bushing 16 formed with an ear 41 pivotally connected by a stud to a toggle-link 15. The other end of this toggle-link is pivotally connected to an arm 42 integral with the bushing 14.

The shaft 17 is secured in the bushing 16 against rotation by means which permit the operator to loosen the shaft and to adjust or turn it through 180° about its axis and to fix it again 55 in its adjusted position. For this purpose, the shaft is provided with a hexagonal head 45 adapted to be engaged by a wrench and the shaft has four recesses 43 spaced 90° apart about the shaft as shown in Fig. 2. The bushing 16 is provided with two tapped bores adapted to receive set screws 18 bearing against the walls of the recesses 43, thus securing shaft 17 in the bushing 16 against longitudinal and angular displacement. 65

After the screws 18 have been unscrewed sufficiently to be withdrawn from the recesses 43, the shaft may be adjusted or turned through 180° about its axis and may then be secured 70 in its adjusted position by tightening the screws 18 again.

The bracket 3 is formed with an annular portion surrounding the tool-holder 10 and carries interchangeable spacers 20 and 21 adapted to 75 limit the pivotal movement of the tool-holder 10.

The operation is as follows:

When the ram 2 moves up and down, the shaft 13 turns alternately one way and the other and tends to impart this motion through the slip-clutch to the bushing 14, whereby the toggle 5 formed by the arm 42 and the link 15 is alternately straightened as shown in Fig. 2 and collapsed. This will have the effect of rocking the shaft 17 in its bearings 37 and 38. The center b of the eccentric 40 turning about the axis a of the 10 shaft 17 oscillates along an arcuate path extending substantially horizontally at the distance e from the axis a. The rocking motion of the eccentric 40 is imparted to the sliding block 19 mounted thereon which is guided between the 15 walls 9 of the slot provided in the tool-holder 10. Therefore, the tool-holder 10 is rocked about shaft 4 within the limits imposed by the spacers 20 and 21. Owing to this to-and-fro motion of the tool-holder 10, the tool-pinion 7 is moved to 20 operative position relative to the blank initially during the operative stroke of the ram and is withdrawn from its operative position at the beginning of the return-stroke of the ram.

The spacers 20 and 21 which determine the 25 amount of the pivotal movement of the tool-holder 10 are so dimensioned that the axis of spindle 6 will be truly perpendicular during the working stroke, that is to say, parallel to the axis of the blank, and that the cutting edges of the 30 tool 7 are sufficiently spaced from the blank during the return-stroke of the ram. When the machine is set to perform the work of cutting inner teeth in an annular blank as shown in Fig. 1, and if the machine is so designed as to perform the 35 operative stroke in downward direction, the spacer 20 is so dimensioned that the tool-spindle assumes its perpendicular position when the holder 10 bears against the spacer 20.

When the ram 2 starts on its downward stroke, 40 the shaft 17 tends to turn in anti-clockwise direction with reference to Fig. 2 owing to the toggle being straightened and, thereby, pivots the holder 10 until the holder bears against the spacer 20. This will bring the toggle to the position illustrated in Fig. 2 in which it is nearly straightened. An abutment 22 of the bushing 16 adapted to 45 operate with the link 15 serves to prevent the toggle from passing through its straightened position.

After the tool-holder 10 has been brought into 50 contact with the spacer 20, the shaft 17 is prevented from continuing to rotate so that the slip-clutch 14 will slip during the continued rotation of shaft 13. When the parts assume this 55 position, the toggle will lock the tool-holder 10 against a retrograde pivotal movement under the reaction of the cutting pressure of the tool 7.

When the working stroke has been finished and the ram starts on its upward stroke, the gear 12 60 reverses its rotation and takes the bushing 14 along with it in the opposite direction, whereby the toggle collapses and leaves its locking position and rotates the shaft 17 in clockwise direction with reference to Fig. 2. Therefore, the 65 tool-holder 10 is pivoted about the shaft 4 towards the right with reference to Fig. 1, until it bears against the spacer 21. The thickness of this spacer is less than that of the spacer 20, the difference in thickness corresponding to the pivotal movement required to withdraw the tool 7 from its operative position. After the holder 10 has been brought in contact with the spacer 21, the shaft 17 will remain at rest during the continued upward motion of the ram. The fric- 70 75

tional force, however, exerted on the shaft 17 by the slip-clutch and the toggle will hold the tool-holder 10 in its position against the spacer 21 until the subsequent downward stroke of the ram begins.

When inner teeth are to be cut, as illustrated in Fig. 1, the movement of the tool into its operative position is in a direction from the right to the left, while it is in opposite direction when outer teeth are to be cut. When it is desired to set the machine for cutting outer teeth, for instance the blank indicated in dotted lines in Fig. 1, the operator unscrews the screws 18 and rotates the eccentric shaft 17 through 180° and then tightens it in its adjusted position. Moreover, he interchanges the spacers 20 and 21 as shown in Fig. 4, said spacers being secured in their position by suitable releasable means not shown in the drawings. This will have the effect of arresting the spindle 6 in its truly perpendicular position, when the tool-holder swings into its right-hand end-position with reference to Fig. 1. It will be noted that, when the tool-spindle 6 assumes its perpendicular position, the tool-holder 10 is spaced equal amounts from the bearing surfaces of the bracket 3 which carry the spacers 20 and 21.

The eccentric will now act in a direction opposite to that when cutting inner teeth and the spacers will secure the spindle 6 in its vertical position during the downward stroke. During the upward stroke of the ram, the tool is lifted from the blank towards the left with reference to Fig. 1.

If desired, the machine could be so arranged as to perform the cutting stroke upwardly and the return stroke in downward direction. In this event, the direction of rotation of gear 12 may be reversed by the interposition between gear 12 and rack 11 of an intermediary gear, or the toggle may be so arranged that it will be straightened by the upward motion of the arm 42 rather than by the downward motion thereof.

The kinematic conditions of my invention are diagrammatically shown in Fig. 4. It will appear from this figure that the function of the settable mechanism is based on the fact that the rocking member formed by the parts 16 and 17 is so constructed as to permit the selective connection with the tool holder 10 either of the point *b* positioned above the pivotal axis *a* or of the point *b'* positioned below said pivotal axis. While this selective connection is established in the embodiment described hereinabove by a turn of the eccentric through 180°, it is obvious to anyone skilled in the art that the rocking member could be also equipped with two eccentric shafts adapted to be alternatively connected with the tool holder 10.

I wish it to be clearly understood that my invention is not limited to the specific details of the embodiment described hereinabove, but is capable of numerous modifications without departing from the spirit of the invention.

What I claim is:

1. In a shaping machine, the combination comprising a reciprocating ram, a tool holder pivoted thereto for movement into and out of operative cutting position relative to a blank and provided with vertical guide-ways, a stationary rack, a rocking member and a gear mounted on said ram, said gear meshing with said rack, a toggle connected to said rocking member, a slip-clutch connecting said toggle to said gear, an eccentric adapted to be optionally connected to said rock-

ing member in either one of two positions, and a sliding block on said eccentric guided in said vertical guide-ways of said tool holder, whereby the machine may be set for operation on a blank positioned on one or the other side of said tool. 5

2. In a shaping machine, a frame arranged with a work supporting table, a ram mounted on the frame to have reciprocating movement toward and away from the work supporting table, a tool holder carried by the ram to participate in the reciprocating movements thereof relative to the work on the work supporting table and to have pivotal movement into and out of operative cutting position relative to the work and arranged with guideways extending longitudinally thereof, a member mounted on the ram to have rocking movement, means to transmit rocking movement to said member from and by the reciprocating movements of the ram, an eccentric means to connect the eccentric in either one of two positions with said rocking member to transmit the rocking movement of said member to oscillatory movement of the eccentric, and a block engaged on the eccentric mounted in the guideways of the tool holder to have sliding movement therein, whereby by the connection of the eccentric with the rocking member the tool holder may be set for operation on the work on the work support on one or the opposite side of the work. 30

3. In a shaping machine, a frame arranged with a work supporting table, a ram mounted on the frame to have reciprocating movement toward and away from the work supporting table and arranged with opposite abutments, a tool holder carried by said ram to participate in the movement thereof toward and away from the work supporting table and to have pivotal movement on an axis transverse of the movement of the ram into and out of operative cutting position relative to the work on the work supporting table and arranged with stop faces on opposite sides thereof in opposed relation to the abutments of the ram, spacers adapted to be interchangeably and releasably mounted on the abutments for engagement of the stop faces of the tool holder and limit the pivotal movement of the tool holder, and means including a toggle operatively connected with the tool holder and operatively connected with the reciprocating movements of the ram to position the tool holder with a stop face thereof in engagement with one spacer during the movement of the ram in one direction and to position with the other stop face thereof in engagement with the other spacer during the movement of the ram in the opposite direction. 45

4. In a shaping machine, a reciprocating ram, a tool holder mounted on the ram to participate in the reciprocating movements thereof and have pivotal movement into and out of operative cutting position, and means to swing the tool holder into and out of cutting position and for locking it in operative cutting position, comprising an eccentric rotatably carried by the ram and operatively connected with the tool holder, a fixed rack, a rotatable shaft carried by the ram, a pinion fixed on said shaft meshing with the rack and thereby adapted to transmit rotative movement in opposite directions to the shaft by the reciprocating movements of the ram, a toggle including a link pivotally connected with the eccentric and a friction member loose on said shaft, and a friction member rotatable with the shaft and urged into engagement with the fric- 75

- tion member of the toggle to couple the shaft with the toggle and thereby the eccentric with the shaft and transmit oscillatory movements to the eccentric by the reciprocatory movements of the ram.
5. In a shaping machine, a frame having a work supporting table and guideways extending at an angle to the surface of the work supporting table, a ram mounted in the guideways to have 10 reciprocatory movements toward and away from the work supporting table, a tool holder carried by the ram to participate in the movements thereof and have pivotal movement on an axis extending transversely of the movement of the 15 ram and adapted to be moved to position with the tool in operative cutting position during the movement of the ram toward the work on the work supporting table and to position with the tool at either side and out of cutting position during 20 the return movement of the ram, means operative from the movements of the ram to swing the tool holder to and hold it in cutting position during the movement of the ram toward the work supporting table and swing the tool holder to predetermined position with the tool at either side of 25 its cutting position and retain it in said position during the movement of the ram away from the work supporting table, said means including set-table means for determining the direction of movement of the tool holder to position the tool out of 30 cutting position during the return movement of the ram away from the work supporting table, whereby to set said means for operation of the tool carried by the tool holder on work positioned on the work supporting table at one or the 35 opposite side of the tool.
6. In a shaping machine, a reciprocatory ram, a bracket fixed on the ram, a tool holder carried by the bracket to participate in the reciprocatory 40 movements of the ram and have movement on an axis extending transversely of the movement of the ram, spacers adapted to be interchangeably mounted on the bracket at opposite sides of the tool holder to be engaged by and limit the pivotal 45 movements of the tool holder and the tool into and out of cutting positions, and means adapted to be connected in either one of two positions to the ram and actuated from the movements of the ram, said means in one of its connections with the ram and in one position of the 50 spacers being operative to engage the tool holder

with one spacer and position the tool holder with the tool in cutting position during the movement of the ram in one direction and engage the tool holder with the other of said spacers and position the tool holder to incline in one direction 5 relative to the plane of movement of the ram and the cutter out of cutting position during the movement of the ram in the opposite direction, and said means in the other connection thereof with the ram and in the other position of the 10 spacers being operative to engage the tool holder with one spacer and position the tool holder with the tool in cutting position during the movement of the ram in one direction and engage the tool holder with the other spacer and position the tool holder to incline in the opposite direction 15 relative to the plane of movement of the ram with the tool out of cutting position during the movement of the ram in the opposite direction.

7. In a shaping machine, a reciprocatory ram, 20 a bracket fixed on the ram, a holder mounted on said bracket to participate in the movement of the ram and have pivotal movement on an axis extending transversely of the movement of the ram, a cutter carrying spindle journaled in said 25 holder to rotate on an axis extending parallelly of the movement of the ram, spacers adapted to be interchangeably mounted on the bracket at opposite sides of the holder, one of said spacers being adapted for engagement of the holder to 30 limit the pivotal movements of the holder to position the cutter carrying spindle with the cutter in operative and out of cutting positions, means connected to and operative from the movements of the ram to move the holder into and 35 hold it in engagement with one spacer and the cutter carrying spindle with the cutter in operative cutting position by and during the movement of the ram in one direction, and to move the holder laterally into and hold it in engagement with the other spacer and the cutter carrying spindle with the cutter out of cutting position by and during the movement of the ram in the opposite direction, and means to connect said 40 latter means in one of two positions with the ram 45 and predetermine the direction of movement of the holder to position the holder and cutter carrying spindle with the cutter out of cutting position at one or the opposite side of the cutting position of the cutter.

50 ERNST AEBERLI.
